UNITED STATES PATENT OFFICE.

ARTHUR LEE, OF NEW YORK, N. Y., ASSIGNOR TO HENRY CHARLES
WATERHOUSE, OF NEW YORK, N. Y.

DESIGN FOR A PLAYING-CARD.

No. 38,295.

Specification for Design.

Patented Oct. 23, 1906.

Application filed September 1, 1906. Serial No. 333,022. Term of patent 14 years.

To all whom it may concern:

Be it known that I, ARTHUR LEE, a subject of the King of Great Britain and Ireland, and a resident of the borough of Manhattan, city, county, and State of New York, have invented a new, original, and ornamental Design for Playing-Cards, of which the following is a specification, reference being had to the accompanying drawing, forming a part thereof.

The drawing shows a plan view of a playing-card embodying my new design.

I claim—

The ornamental design for a playing-card as shown.

ARTHUR LEE.
